Inventor

UNITED STATES PATENT OFFICE

ANTONIO J. CASALE, OF WASHINGTON, DISTRICT OF COLUMBIA

CULINARY APPLIANCE

Application filed November 5, 1928. Serial No. 317,400.

This invention relates to culinary appliances.

An object of the invention is to provide a device of the class described which can be used for lifting and serving solid or semi-liquid foods.

Another object of the invention is to provide a device which is capable of being quickly detached to permit the user to adapt the implement to various uses in the kitchen.

Another object of the invention is to provide a spring and wedge connection for the various parts of the appliance, whereby the sections may be separated at their pivot point, or if occasion arises, the gripping ends may be interchanged or others substituted, as found necessary.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows, in side elevation, a device constructed in accordance with the invention, parts being shown in section,

Figure 2 is a view at right angles to Figure 1, parts being shown in section,

Figure 3 is a fragmentary perspective view showing the means for attaching the gripping ends of the appliance,

Figure 4 is a sectional view taken on the line 4—4 of Figure 2,

Figure 5 is a sectional view taken on the line 5—5 of Figure 2,

Figure 6 is a fragmentary perspective view of one of the pivoted members showing the pivot element and the spring member of the spring and wedge connection, and

Figure 7 is a similar view of the other pivoted member showing the wedge member of the spring and wedge connection.

In carrying out the invention, there is provided a pair of oppositely disposed pivoted

arms 1 and 2 having handles 3 and 4, respectively.

The arm 1 carries a pivot element 5, mounted in a counter-bored opening 6 and supplied on its screw-threaded end with a nut 7 whereby the pivot element 5 is held securely in position.

Formed on one end of the pivot element 5 is a head 8 which is adapted to pivotally hold a resilient connecting socket 9 constituting a part of the spring and wedge connection hereinbefore mentioned. The resilient connecting socket 9 includes flanges 10 formed on its longitudinal edges for a purpose to be herein-after more fully described.

The pivoted arm 2 has a wedge or key 11 formed on its inner face opposite the resilient connecting socket 9 and adapted to be inserted therein in assembling the device.

The longitudinal edges of the wedge or key 11 are formed with diverging bevels 12 for cooperation with the spring flanges 10 of the resilient connecting socket 9, whereby a dove-tailed joint is effected to securely hold the wedge 11 within the connecting socket 10 against accidental displacement.

The ends of the pivoted arms 1 and 2, remote from the handles 3 and 4, are reduced as shown at 13, and have secured thereto, either by rivets 14 or by welding, resilient connecting sockets 15, similar to the sockets 9 already described.

Wedges or keys 16, similar to the wedge 11, are secured to the shanks 17 of implements 18 and are adapted for cooperation with the resilient connecting sockets 15 to hold the implement in position during use.

A fork and a spoon are shown in the drawing, but it is to be understood that two forks or two spoons may be substituted as desired. The implements 18, being detachable and interchangeable, it is apparent that any combination of kitchen implements may be used without departing from the spirit of the invention.

In assembling the device for use, the implements 18 are selected and attached to the ends 13 of the arms 1 and 2 by forcing the wedges or keys 16 into the resilient sockets 15. The resilient socket 9 on arm 1 is then

turned on its pivot 5 to the position shown in Figure 6 and the wedge or key 11 on the arm 2 is forced therein. The appliance is then ready for use by one hand of the user.

5 Should the user desire to manipulate the implement separately or one in each hand the spring and wedge connection composed of the members 9 and 11 are forced apart quickly and without the use of tools.

10 What is claimed is:—

1. A device of the class described including a pair of arms having handles on one of their ends and gripping implements on their other ends, a resilient socket pivoted to one

15 of the arms intermediate its ends, and a wedge secured to the other arm for insertion in the resilient socket to permit a pivotal movement of the arms relative to each other.

2. A device of the class described including a pair of arms having handles on one of their ends and gripping implements on their other ends, a socket pivoted to one of the arms intermediate its ends, and a key secured to the other arm for insertion in the socket to permit a pivotal movement of the arms relative to each other.

3. A device of the class described including a pair of arms, a socket pivoted to one of the arms intermediate its ends, a pivot 30 element for securing the socket to one of the arms, and a tapered key for insertion snugly within the socket, said tapered key being secured to the other arm opposite to the pivoted socket.

35 4. A detachable connector for separable and interchangeable elements of a culinary appliance including a tapered key having diverging longitudinal sides secured to one of the separable members, a tapered socket 40 having longitudinal resilient flanges for snugly engaging the diverging sides of the tapered key to prevent accidental displacement, and means for securing the tapered socket to the other of the separable members.

45 5. A detachable connector for separable and interchangeable elements of a culinary appliance including a key having diverging longitudinal sides secured to one of the separable members, and a socket having longitudinal resilient flanges for snugly engaging the diverging sides of the key, to prevent accidental displacement, secured to the other of the separable members.

In testimony whereof I affix my signature.

55 ANTONIO J. CASALE.
